DESIGN FOR AN ANDIRON

Edward J. Burns, Pittsfield, Vt.

Application December 14, 1945, Serial No. 124,753

Term of patent 7 years

(Cl. D81—6)

To all whom it may concern:

Be it known that I, Edward J. Burns, a citizen of the United States of America, and a resident of Pittsfield, in the county of Rutland and State of Vermont, have invented a new, original, and ornamental Design for Andirons, of which the following is a specification, reference being had to the accompanying drawing, forming a part thereof, wherein

Fig. 1 is a side elevational view of an andiron showing my new design;

Fig. 2 is a front elevational view thereof; and

Fig. 3 is a top plan view thereof with the log-supporting portion shown in Fig. 1 omitted.

The dominant features of the design reside in the portions shown in full lines.

I claim:

The ornamental design for an andiron, substantially as shown and described.

EDWARD J. BURNS.
